(57) **CLAIM**

The ornamental design for a hub for a surgical blade, as shown and described.

DESCRIPTION

FIG. 1 is a perspective view of a hub for a surgical blade in accordance with the new design;

FIG. 2 is a front view of the hub for a surgical blade of FIG. 1;

FIG. 3 is a rear view of the hub for a surgical blade of FIG. 1;

FIG. 4 is a right side view of the hub for a surgical blade of FIG. 1;

FIG. 5 is a left side view of the hub for a surgical blade of FIG. 1; and,

FIG. 6 is a top view of the hub for a surgical blade of FIG. 1.

In the drawings, the broken lines illustrate environmental subject matter that forms no part of the claimed design.

1 Claim, 6 Drawing Sheets
